UNITED STATES PATENT OFFICE

JESSE H. DAVIS, OF BALTIMORE, MARYLAND

WINDOW OPERATING DEVICE

Application filed May 6, 1930. Serial No. 450,199.

The object of my invention is to provide an electrically controlled and pneumatically operated window operating device, which, for purposes of illustration, I have shown especially adapted for use in connection with a passenger vehicle.

While I have shown my invention embodied in the electro-pneumatic type, it will be understood that it may be mechanically controlled and pneumatically operated.

In the drawings:

Figure 1 is a front elevation of the window embodying my invention.

Figure 2 is a vertical central section of Figure 1.

Figure 3 is an enlarged detail elevation illustrating my invention.

Figure 4 is an enlarged detail edge elevation of Figure 3, partly broken away.

Figure 5 is an enlarged detail sectional view of the sash lock and a portion of the lift plunger.

The reference numeral 1 designates a passenger vehicle window, of the double sash type, which is so commonly now used in passenger cars or vehicles, but, of course, it will be understood that my invention is equally effective with the single sash type of window. The sashes 2 and 3 are of commercial type.

The rail and stiles 4, 5 respectively, have a suitable bore 6 which register, into which the upper end of the plunger, piston or push rod 7 enters and is anchored, said plunger having a transverse slot 8 into which the outer end of the plunger bolt 9 projects, said bolt being of the bell crank lever type, one end of which functions as an operating handle 10. This bolt is pivoted at 11 in a casing 12, which is provided with a recess 13, in which is mounted a rod 14 on which a coil spring 15 is mounted, one end of the spring being seated on the support 16, while its other end is seated on the shoulder 17 of the sash lock bolt 18. This bolt 18 is adapted to be projected by the spring 15 beyond its casing 12 to engage a suitable keeper 19 on the window frame which may be of any desired construction. The spring 15 maintains the bolt 18 in its projected locking position normally, but when

the handle 10 is operated the spring is compressed and the bolt 18 withdrawn from engagement with the keeper 19 by reason of the fact that the handle passes through a slot 21 in the bolt. In order to accommodate the vertical movement of the outer end of the plunger bolt 9 the slot 8 in the plunger is elongated, as shown. A suitable filler 22 is secured to the bottom edge of the sash, through which the piston travels.

The piston, or push rod 7, is slidably mounted in the casing or cylinder 23, said rod, if desired, having a piston head.

The electro-pneumatic valves 24, 25, are connected through the pipes 26 to the pipe 27, which pipe 27 is in turn connected with the usual emergency reservoir on the vehicle. The valves 24 and 25 are connected by pipes 28 to the pipe line 29, which in turn is connected to the piston casings or cylinders 23.

When double sashes are used, two push buttons 30 and 31 are employed, one for each sash, and placed in a position for convenient use by the passenger. These buttons are wired, preferably as shown (32) to the valves 24, 25. The wire 33 is in direct circuit with the usual vehicle battery, while the wire 34 leads to the said usual battery.

When the push button is depressed the electro-pneumatic valve admits air to the cylinder 23 whereupon the piston starts to rise and operates the plunger bolt 9 to throw the bolt 18 out of engagement with its keeper 19, thus freeing the sash to move upward to any desired open position under the pushing action of the push rod 7 and the air in cylinder 23. This movement continues so long as the push button is held in its depressed position, or until the sash has completed its movement where it is held by the latch bolt 18. When the pressure on the push button is removed the electro-pneumatic valve automatically opens an exhaust port so that the air pressure in the cylinder 23 is released.

The windows may be raised and lowered by hand in the usual manner in the event of any disarrangement or breakdown of the power raising device.

The amount of compressed air required is so slight that with all the windows in the car,

on all cars in the train equipped with this device, there is no likelihood of reducing the air pressure so as to cause brake application. The amount of electrical energy required for each push button is only about three-tenths of one ampere for the moment that the push button is depressed. Consequently, the demand for electricity is very low, indeed, and will in no wise constitute a drain upon the batteries, or the lighting system which would appreciably affect its capacity.

The design and construction of the entire mechanism is such that it will require no maintenance or lubrication from shopping to shopping of the car.

The compressed air is taken from the emergency reservoir on the car, or other suitable source. The electricity is taken from the car lighting system or the batteries in connection therewith.

The push button may be separate, or it may be combined with the handle of the latch in such manner that when the latch handle is depressed by hand, as is normally done in raising a sash by hand, the electro-pneumatic valve would admit air to the cylinder 23 and the window would move upward unattended by any effort of the operator other than to depress the latch handle. The sash would be secured in any desired position by the spring 15 of the latch causing the bolt of the same to engage a keeper in the usual manner.

When the cars are parked, it is desirable, and in many cases necessary, to have the windows locked so as to prevent opening from the outside. It is obvious from the disclosure herein that this is accomplished by reason of the fact that the latch 18 engages the keeper at all sash positions, and it can only be withdrawn from the keeper by hand pressure in the usual manner, or by depressing the push button, if a separate push button is provided, both of which acts can only be performed from within the car.

The device provides for two one inch air cylinders for each sash, one on each side, both controlled by one electro-pneumatic valve. When the windows are double sashed four air cylinders and two electro-pneumatic valves would be required. My tests in cars, however, have indicated that one cylinder to each sash may be adequate in which event for double sashed windows only two cylinders 23 would be required for raising. Two electro-pneumatic valves, or possibly one, might be arranged to function with two windows.

This electro-pneumatic valve is a standard product and has two seats or ports. The normal position is the upper port which is open to the atmosphere. When the push button is pressed the upper port is closed and the lower port is opened against spring compression. Compressed air from the emergency reservoir or other source then enters through the lower port and passes into the cylinder

which causes the window to raise. During this operation the upper port of course is closed. The moment that the pressure on the push button is released the spring in compression at the bottom raises the valve thus opening the port at the top and closing the one at the bottom. This act immediately releases to atmosphere the air which is in the cylinders.

An air cylinder or cylinder of suitable dimensions may be placed beneath the windows to be raised or may be located overhead or in any desired position. This has reference to the air cylinders used for raising or lowering the windows. In other words, on a car constructed in a certain manner I may desire to place these cylinders for raising or lowering the windows in a horizontal position or above the window rather than in a vertical position immediately below as I have shown. Any desired position can be used by suitable translating mechanism to impart an up and down motion to the window.

What I claim is:

1. In a window, a device for locking and operating the sash of the window, said device including a latch to lock the sash in the desired position, a power operated device coupled to the latch to release the latch and operate the sash, a power supply, and an electro-pneumatic valve to control the operation.

2. In a window, a device for locking and operating the sash of the window, said device including a pivoted latch to lock the sash in the desired position, and an electrically controlled and pneumatically operated device coupled to the latch to release said latch and operate the sash.

3. In a window, a device for locking and operating the sash of the window, said device including a normally manually operated latch to hold the sash in the desired position, and an electrically controlled and pneumatically operated member coupled to the latch for releasing said latch and operating the sash.

4. In a window, a device for locking and operating the sash of the window, said device including a latch, a pneumatically operated member attached to the latch for releasing said latch and operating said sash, an electro-pneumatic valve controlling said member, and a push button in the window frame to control said valve.

5. In a window, a device for locking and operating the sash of the window, a latch, a pneumatically operated member attached to said latch for releasing the latch and operating the sash, an electro-pneumatic valve controlling said member, and a push button in the window frame to control said valve, said latch being manually operable independently of said member.

6. In a window, a device for locking and operating the sash of the window compris-

ing a spring actuated latch to engage the sash, a pivoted operating member connected to the latch, a piston connected to the latch operating member for directly releasing said latch and transmitting motion through said latch operating member to the latch, and means for operating the piston.

6 7. In a window, a device for locking and operating the sash of the window comprising a piston, a latch comprising coupled members, one to engage the window frame to lock the sash in closed position and the other to engage the piston, and means for operating the piston, the latch members and piston being coupled for operation whereby the piston is adapted to directly release the latch and through the latch then transmit motion to the window.

10 8. In a window, a device for locking and operating the sash of the window comprising a sliding latch member for locking the latch, a spring acting thereon for holding said latch member projected, a piston, a pivoted latch member engaging the piston and adapted to be operated thereby to retract the sliding latch member and transmit motion to the window, and a handle on the pivoted latch member whereby said member may be operated for manually retracting the sliding

30 latch member.

9. In a window, a device for locking and operating the sash of the window including a latch to lock the sash in the desired position, said latch having a pivotally mounted member, a plunger connected to said latch member and acting on the latch for releasing the latch and transmitting motion through the latch to the sash, and valve controlled fluid pressure means governing said member.

40 10. In a window, a device for locking and operating the sash of the window including a sliding latch to lock the sash in the desired position, a pivotally mounted member for transmitting movement thereto, a spring for holding the latch projected, a fluent power operated member connected to the pivotally mounted member for actuating the same to release the latch and transmit motion through the latch to the sash, and a control member governing said power applying means.

50 11. In a window, a device for locking and operating the sash of the window including a pivoted latch to lock the sash in the desired position, a fluid pressure operated device coupled to the latch to release the latch and transmit motion therethrough to the sash, and an electro-pneumatic valve controlling said device.

60 In testimony whereof I affix my signature.
JESSE H. DAVIS.
